UNITED STATES PATENT OFFICE.

ALBERT W. BRASH, OF NEWARK, SOUTH DAKOTA.

SILO.

1,335,649.

Specification of Letters Patent. Patented Mar. 30, 1920.

Application filed October 13, 1919. Serial No. 330,265.

To all whom it may concern:

Be it known that I, ALBERT W. BRASH, the above-named petitioner, being duly sworn, depose and say that I am a citizen 5 of the United States, residing at Newark, in the county of Marshall and State of South Dakota, that I verily believe myself to be the original, first, and sole inventor of Improvements in Silos, of which the following

is a specification.

This invention relates to silos and particularly to cylindrical wooden stave silos.

It has been found that considerable shrinkage takes place between the staves 15 forming the usual cylindrical, wooden stave silos, causing leakage and often the collapsing of the wall due to loosening of the bands or hooks. It is the primary object of my invention to remedy this condition by providing an automatic means for taking up 20 shrinkage as it occurs.

Another object of the invention is to utilize to a maximum extent the elements forming the usual stave silo in order that the 25 present device may be incorporated therein without effecting a change in the entire silo construction.

Other objects and advantages will be fully explained in the following description and 30 the invention will be more particularly pointed out in the claims.

Reference is had to the accompanying drawings which form a part of the specification.

Figure 1 is a perspective view of a silo having my device applied thereto.

Fig. 2 is a detail view of the invention.

Fig. 3 is a sectional view showing to advantage the metal retainer.

Similar characters of reference are used to 40 indicate the same parts throughout the several views.

It is to be understood that the present invention is to be applied to the usual form 45 of stave silo indicated in the drawing by the letter A and having a foundation B. As shown each of the silo staves is provided with a groove on one edge and a tongue on the other forming the usual tongue and 50 groove joint and are held together with a plurality of the usual sustaining bands or hoops indicated by C.

As is clearly illustrated in detail in Fig. 2 of the drawing my invention contemplates 55 the use of a diametrically split stave having complementary opposed wedge sections

1 and 2 one of which (indicated by 1) is movable with respect to the other, a tongue and groove joint being effected between the two and also between the adjacent staves 3 60 and 4. Attention is called to the fact that any one of the conventional staves forming the silo may be split in the manner indicated and utilized for the purposes of the present invention.

Mounted adjacent the broad end of the movable stave 1 is a pulley 5 over which is trained the rope or chain 6 having one end thereof connected to an eye bolt in the foundation 7 and the other end to a weight of suitable size 8. As illustrated the weight has a pair or eyes 9 through which is trained the section of the rope 6 which is attached to the foundation. This prevents swaying or displacement of the weight.

It will be seen that the action of the weight is to draw the movable section 1 downward, thus exerting a pressure upon the staves 3 and 4 and consequently tightening all the staves forming the body of the 80 silo.

Suitably mounted either on the section 2 of the stave or upon the stave 4 and on the interior of the silo is a board or sheet metal retainer 10 adapted to extend in back of the 85 movable section 1 in order to close the opening between the small end thereof and the foundation.

In connection with the present invention it is also desirable to use dowel pins in addition to the above tongue and groove connection in order to prevent longitudinal movement of the respective staves forming the silo with respect to each other.

While I have shown and described the 95 preferred embodiment of my invention it will be understood that minor changes in construction, combination and arrangement of parts may be made without departing from the spirit and scope of the invention as 100 claimed.

What I claim is:

1. A silo including a plurality of staves, one of said staves split to form sections, means for reinforcing and preventing leakage between the sections, one of said sections being movable with respect to the other of said sections and means for automatically drawing said movable stave section downwardly to take up shrinkage between the 110 remaining staves.

2. A silo including a plurality of staves,

one of said staves split diametrically to form upper and lower wedge shaped sections, one of said sections being movable with respect to the other of said sections 5 and means for automatically drawing said movable stave section downwardly to take up shrinkage between the remaining staves.

3. A silo including a plurality of staves, one of said staves split diametrically to form 10 upper and lower wedge shaped sections one of said sections being movable with respect to the other of said sections, a pulley on the movable section, and a weight connected with the pulley for drawing the section 15 downwardly to take up shrinkage between the remaining staves.

4. A silo including a base and a plurality of staves, one of said staves split diametrically to form upper and lower wedge shaped sections one of said sections being movable 20 with respect to the other of said sections, a pulley adjacent the upper extremity of the movable section, a weight, means connected

with the base portion of the silo and trained over the pulley for attachment to the weight 25 to draw the removable section downwardly to take up shrinkage between the remaining staves, and means for preventing swinging of the weight for the purpose set forth.

5. A silo including a base and a plurality of staves, one of said staves split diametrically to form upper and lower wedge shaped sections, one of said sections being movable with respect to the other of said sections, means for automatically moving one section with respect to the other for taking up shrinkage between the remaining staves, and means secured to the immovable section interiorly of the silo and extending across the point of contact between the two 40 sections to reinforce and prevent leakage between the two sections for the purpose set forth.

In testimony whereof, I affix my signature hereto.

ALBERT W. BRASH.
